PENDULUM TYPE SOOT BLOWER

De Los E. Hibner and Fred C. Arey, Du Bois, Pa.,
assignors to Vulcan Soot Blower Corporation,
a corporation of Pennsylvania

Application December 24, 1941, Serial No. 424,222

5 Claims. (Cl. 122—392)

It is common practice to provide steam power plants with soot blowers for removing soot and ashes from the surfaces of the tubes through the walls of which the water and steam are heated. In some installations the tubular jetting elements at all times remain in working position with respect to the tubes and are thus continuously subjected to the heat of the furnace. In other installations the tubular jetting elements are so mounted that they may swing, in the manner of a pendulum, between an extended working position in the heating zone and an idle position beside the furnace wall where they are protected against the intense heat of the furnace while idle. The present invention relates particularly to this second type of apparatus and has for one of its objects to insure that the jetting elements are subjected to the cooling influence of the cleaning fluids at all times except when at rest in their idle positions.

It is also common practice to supply cleaning fluid, particularly steam, to the jetting elements through heads provided with means for turning tubular blowing elements about their long axes and containing valves for controlling the flow of cleaning fluid, which valves are caused to open and close automatically at the ends of a cycle of operation. A further object of the present invention is so to modify soot blower heads of this kind as to permit them to swing jetting elements in the manner of a pendulum, or otherwise, instead of rotating them, and automatically to supply steam or other cleaning fluid from the beginning of such swinging or other movement until the time an element is returned into its idle position.

The various features of novelty whereby our invention is characterized will hereinafter be pointed out with particularity in the claims; but, for a full understanding of our invention and of its objects and advantages, reference may be had to the following detailed description taken in connection with the accompanying drawings, wherein:

Figure 1 is a more or less diagrammatic view in the nature of a vertical section through a furnace wall having one of our improved blower units mounted therein, the jetting element being shown in full lines in its idle position and in dotted lines in its working position; Fig. 2 is a view partly in side elevation and partly in section, of one of the heads, a fragment of the element attached thereto, and the supporting housing from which the outer or cover section has been removed; Fig. 3 is a section on a smaller

scale, on line 3—3 of Fig. 2; Fig. 4 is a section on line 4—4 of Fig. 3, on a still larger scale; Fig. 5 is a section taken approximately on line 5—5 of Fig. 2; and Fig. 6 is a top plan view of a fragment of the operating shaft, the lever arm for moving the pilot valve in one direction, and the cam for operating said lever arm.

Referring to the drawings, 1 represents a furnace wall having therein a long, narrow, vertical opening in which is fitted and fixed a housing 2 open on the inner side of the furnace wall and projecting a substantial distance outwardly from the furnace wall. The housing may conveniently be divided into two sections on a plane near the outer end or side and parallel with the furnace wall; the outer section 3 being secured to the main portion of the housing in any suitable way which permits separation of the two sections when desired. Clamped between the two sections of the housing are two bearings 4 through which extends a rotatable tubular element 5 closed at one end and extending at its other end into a suitable head in which it is rotatable and from which it receives cleaning fluid. The member 5 forms with a short tubular section 6, of about the same diameter as the member 5, a T, the stem of which projects a little into the furnace chamber when it is horizontal, as shown in full lines in Fig. 3, and lies wholly in the part of the housing outwardly from the furnace wall when in the vertical position, as shown in dotted lines in Fig. 3. The actual jetting or blowing element 7 is connected to the end of the tubular member 6 so as to be positioned at right angles thereto; the axes of the member 6 and the element 7 lying in a vertical plane at right angles to the furnace wall and to the axis of the tubular journal portion 5. Normally, while no jetting or blowing is being done, the element 7 hangs down as shown in full lines in Figs. 1 and 3, close to the inner face of the furnace wall. The working position of the element 7 is indicated in dotted lines in Figs. 1 and 3.

The blower head into which one end of the journal element 5 extends may be substantially like that illustrated in our prior Patent No. 1,995,198, namely a hollow head portion, proper, 8 provided with a main valve 9 and a pilot valve 10, as indicated in Fig. 5, together with suitable means for holding and turning the member 5. Thus, the member 5 extends through a stationary gear casing 11 fixed to the head 8, and thence through a stuffing box 12 at the entrance to the head. The head as a whole is supported from a suitable cantilever arm 13 fixed to and projecting

laterally from the main section of the housing 2 above and parallel with the axis of the journal member 5. In the arrangement shown, there is a strap 14 extending around a cylindrical portion of the head, just behind the stuffing box namely, at about the center of gravity of the head unit. One or more screw threaded rods 15 extend up through a sturdy cross arm 16 on the cantilever 13. Nuts 17 on the upper end of the rod or rods 15 transfer the load to the arm 16 and permit accurate adjustments to be made in the vertical direction. The gear case may likewise be supported from the cantilever arm through an ear or ears 18. Within the gear casing is a large gear wheel 19 fixed to the journal member 5. Meshing with this gear wheel is a pinion 20 fixed to a shaft 21 lying above the hollow head 8 and parallel with the axis of the journal member. Upon turning the shaft 21 in one direction, the jetting element 7 is caused to swing from its idle position into its working position whereas, upon reversing the direction of rotation of the shaft, the jetting element is returned to its idle position. In order to counter-balance the jetting element so that it will tend to remain in any angular position into which it is moved, we fix upon the free closed end of the tubular journal member 5 a large gear wheel 22 that meshes with a pinion 24 rotatable on a horizontal stub shaft 25 projecting from the main section of the housing 2 on the side opposite from that on which the cantilever arm is located. This pinion may be on or constitute the hub of a sheave 26 upon which is wound a cable 27. From the cable hangs a weight 28. The sheave is preferably provided with a spiral groove 29 for a cable which causes the leverage of the counter-balancing weight to vary with the angle at which the tubular jetting element may be standing at any given instant.

It is desired, as in our aforesaid patent, that the pilot valve be operated and cause the main steam valve to open, upon turning the shaft 21. However, it is our desire that steam be admitted to the jetting element before the same leaves its idle position where it is protected against the heat of the furnace. Means are therefore provided for causing the preliminary movement of the actuating handle or the like to result in opening the pilot valve while the shaft proper 21 remains stationary; this shaft only beginning to turn after sufficient time has elapsed to allow steam to flow through the jetting element. In the arrangement shown, the outer end of the shaft 21 extends through a sleeve 30 through which the actual driving of this shaft is effected. The sleeve 30 extends into a gear casing 31, provided with a long tubular stem 32 through which extends an operating shaft 34. The tubular stem with the enclosed shaft 34 extend down from the head, preferably in a manner to diverge somewhat from the face of the furnace wall. On the lower end of the shaft 34 is a hand wheel 35 so that, by turning the hand wheel, the sleeve 30 may be turned in either direction. The actual driving of the shaft 21 is effected through engagement of a lug 36 projecting radially from the sleeve 30, with a lug 37 fixed to the shaft 21. This permits relative rotary movements between the sleeve 30 and the shaft 21 through an angle of more than one hundred eighty degrees. This lost motion is utilized to open the pilot valve at the beginning of a cycle of operations. As best shown in Fig. 5, there is mounted on one side of the hollow head 8, so as to be rockable in a plane at right angles to the axis of the shaft 21, a lever 38, the lower

end of which is provided with an adjustable stop 39 adapted to engage with the outer end of the pilot valve stem 40 to push the pilot valve inwardly. The upper end of the lever extends into the vicinity of the shaft 21 and the sleeve 30 and has thereon a laterally-projecting pin 41. This pin is adapted to be engaged by a spring-pressed latch 42 to hold the lever in what may be termed its working position, namely that position in which the pilot valve has been pushed back so as to cause the main valve to open. Whenever it is free to do so, the latch assumes a latching position in which the pin 41 engages with an end edge of the latch.

The lever 38 is driven in the direction to actuate the pilot valve by a cam 44 on the sleeve 30. This cam and the lug 36 may conveniently constitute a single integral piece fixed to the sleeve. Normally, when the jetting element is hanging down in its idle position, the lug 36 may be in engagement with the righthand side of the lug 37 as viewed in Fig. 5, so that the cam 44 is remote from the cam roller 45 on the extreme upper end of the lever 38. When the hand wheel is turned for the purpose of starting a blowing operation, the first result is for the cam to come into contact with the cam roller so as to shift the lever and cause the pilot valve to be actuated. A continued turning of the sleeve and cam brings the lug 36 into engagement with the lefthand side of the lug 37, so that now the shaft 21 begins to turn. Before the cam leaves the cam roller, the latch must be permitted to drop in front of the pin 41 on the lever so as to hold the pilot valve against return movement until the latch is again tripped. The tripping of the latch is effected by means of a rocker shaft 46 mounted on the head parallel with the shaft 21. One end of the rocker 40 shaft extends into the gear casing 31 where it is provided with a radial finger 47 lying in the path of a lug 48 projecting from the face of the gear wheel 19. The parts are so proportioned that whenever the jetting element is just about to reach its idle position, the lug 48 engages the finger 47 and turns the shaft 46 through a small angle by the time that the jetting element comes to rest. The shaft 46 extends into the vicinity of the latch 42 and is there provided with a second radial finger 49 from the side of which projects a pin 50 that engages with the side of a downwardly-extending part 51 on the end of the latch farthest removed from the pilot valve actuating lever. The parts are so proportioned that at the time the jetting element comes to rest in its idle position the pin 50 holds the latch in about the position illustrated in Fig. 5, namely, with its latching end a little below the path of travel of the pin 41 on the lever 38. Consequently, as soon as the jetting element reaches its idle position, the latch is tripped and, the cam 44 being now remote from the cam roller, the lever 38 is no longer restrained, and the pilot valve can force it to swing in a clockwise direction, as viewed in Fig. 5, thereby bringing about a closing of the main valve in the head and the shutting off of the steam supply to the jetting element.

Since the latch is locked in an inoperative position while the jetting element is in its idle position, the latch must be released from this restraint while the cam is still engaging with the cam roller. Consequently, the cam is so shaped that it holds the lever in position to keep the pilot valve open until after the lug 36 has

engaged the lug 37 and has caused the shaft 21 to turn far enough to free the latch and allow it to snap up in front of the pin 41 on the actuating lever for the pilot valve.

It will therefore be seen that we have provided means for insuring that cooling fluid will always flow through the jetting element, as long as there is a supply of such fluid available, while said element is in any other position than that in which it is least influenced by the furnace heat. For this reason the jetting element possesses a longer useful life than is true in other installations embodying jetting elements that remain in the furnace chambers at all times as does our jetting element.

While we have illustrated and described with particularity only a single preferred form of our invention, we do not desire to be limited to the exact structural details thus illustrated and described; but intend to cover all forms and arrangements which come within the following definitions of our invention, in which the expression "working position" includes any of the various positions which the jetting element may assume upon being shifted out of its idle position.

We claim:

1. In combination, a tubular blowing element supported for swinging movements between an idle position and a working position, means including a valve for admitting cleaning fluid to said element whenever the valve is open, means acting first to open said valve and then to swing said element from its idle position to its working position, and back again to the idle position, and means, including a part on and movable with said element, to cause the valve to close when said element reaches its idle position.

2. In combination, a tubular blowing element supported for swinging movements between an idle position and a working position, means including a self-closing valve for admitting cleaning fluid to said element whenever the valve is open, a catch to hold the valve open after being opened, means acting first to open said valve and then to swing said element from its idle position to the working position and back again to the idle position, and means actuated by said element to trip the catch when said element returns to the idle position.

3. In combination, a tubular blowing element supported at one end for swinging movements

about a horizontal axis between an idle position and a working position, a sheave rotatable about an axis parallel to the axis about which the element swings and connected to the latter for rotation in unison therewith, a weighted cable wound on said sheave to counter-balance said element, means including a valve for admitting cleaning fluid to said element, means to open said valve and to swing said element from its idle position to its working position, and back again to the idle position, and means, including a part on and movable with said element, to cause the valve to close when said element reaches its idle position.

15 4. In combination, a tubular blowing element supported at one end for swinging movements about a horizontal axis between an idle position and a working position, a sheave rotatable about an axis parallel to the axis about which the element swings and connected to the latter for rotation in unison therewith, a weighted cable wound on said sheave to counter-balance said element, means including a self-closing valve for admitting cleaning fluid to said element, a catch to hold the valve open after being opened, means to open said valve and to swing said element from its idle position to the working position and back again to the idle position, and means actuated by said element to trip the catch when said element returns to the idle position.

5. The improvement in a blower unit wherein there is a rotatable tubular member, a two-position movable element for controlling the admission to said member of fluid to be discharged, 35 a latch to hold said element in one of its positions, a part driven by said tubular member to trip and hold the latch when said member is in a predetermined angular position, and a shaft for turning said tubular member: which comprises an actuator for the shaft having a limited movement relative thereto about the axis of the shaft, and a cam on said actuator for moving said element far enough to cause fluid to be admitted to said tubular member before the lost 40 motion between the actuator and the shaft is taken up upon moving the actuator in one direction and then to hold said element in position to be latched while the shaft is turned far enough to cause said part driven by the tubular member 45 to release the latch.

DE LOS E. HIBNER.
